UNITED STATES PATENT OFFICE.

LORENZ W. STOLZ, OF BEAUMONT, TEXAS, ASSIGNOR TO L. W. STOLZ MARBLE & GRANITE WORKS, OF JEFFERSON COUNTY, TEXAS.

DESIGN FOR A MONUMENT.

Application filed December 15, 1922. Serial No. 4,600. Term of patent 7 years.

To all whom it may concern:

Be it known that I, LORENZ W. STOLZ, a citizen of the United States, residing at Beaumont, in the county of Jefferson and State of Texas, have invented a certain new, original, and ornamental Design for Monuments, of which the following is a specification.

The accompanying drawing which forms a part of this application is a perspective view of a monument of my said new design and illustrating the new and ornamental characteristics thereof.

What I claim is:

The ornamental design for a monument herein shown.

In witness whereof, I have hereunto set my hand and seal at Beaumont, Texas this 9th day of December, A. D. nineteen hundred and twenty-two.
